UNITED STATES PATENT OFFICE

172,672

BARBECUE

Stanley D. Lennox, Los Angeles, Calif., assignor to
El Brazero of California, a corporation of California

Application April 28, 1951, Serial No. 15,003

Term of patent 14 years

(Cl. D81—10)

To all whom it may concern:

Be it known that I, Stanley D. Lennox, a citizen of the United States of America, residing in Los Angeles, county of Los Angeles, and State of California, have invented a new, original, and ornamental Design for a Barbecue, of which the following is a specification, reference being had to the accompanying drawing, forming part thereof.

Fig. 1 is a top plan view of a barbecue, showing my new design, the grate shown in Fig. 2 being omitted.

Fig. 2 is a side elevational view thereof, in quarter section.

The dominant features of the design are shown in the drawing in full lines.

I claim:

The ornamental design for a barbecue, substantially as shown and described.
